UNITED STATES PATENT OFFICE.

LYDIA ROSS, OF WATERTOWN, MASSACHUSETTS.

ABDOMINAL SUPPORTER.

No. 896,583.

Specification of Letters Patent. Patented Aug. 18, 1908.

Application filed May 20, 1907. Serial No. 374,665.

To all whom it may concern:

Be it known that I, LYDIA ROSS, a citizen of the United States, and resident of Watertown, county of Middlesex, State of Massachusetts, have invented certain new and useful Improvements in Abdominal Supporters, of which the following is a specification.

The object of the invention is the construction of an abdominal supporter upon anatomical lines which shall accurately fit the body, shall remain in position without perineal straps, shall allow free play to the muscles used in holding the body upright, shall avoid downward pressure upon viscera and afford efficient support to the abdomen and its contents by drawing comfortably upon the strong, well covered pelvic bones. Provision is also made for the avoidance of the stretching of the goods of which the supporter is made.

In the accompanying drawings: Figure 1 is a side view of my improved abdominal supporter upon the person of the wearer; Fig. 2 is a perspective view of the supporter; Fig. 3 is a view of the several strips or pieces used in the construction of the "back" of the supporter; Fig. 4 is a similar view of the pieces used in the construction of the "front" of a supporter; Fig. 5 is an elevation of one end of the "back" illustrating the manner of attaching the buckles. Fig. 6 is a view of the pieces used in the construction of the front of a supporter, embodying the present invention, for a rounded abdomen. Fig. 7 is a view of the front of the supporter for a rounded abdomen.

In cutting out the several strips or pieces from the fabric of which the supporter is made, straight lines (so designated) are cut with or along the weft of the fabric and at right angles to the warp, or vice versa, in order, as will hereafter appear, that the prevailing line of tension of the finished garment around the body shall come upon a straight, not a diagonal, line of the fabric weave, especially in the back which is without straps or any transverse reinforce. Beginning with one of the two back middle strips *a*, *a'*, of the supporter, I cut it with a straight front edge on a thread of the goods while the back edge I cut with a slight slant or curve upwards, thus making the bottom edge of the strip wider than the top edge. The two curved edges of the two back middle strips *a* and *a'* are united in a seam which

will conform to the curve of the sacrum between the broad iliac bones of the pelvis. The next strip *b* (confining myself now to one-half of the back of the garment, for the two halves are alike), I also cut with the front edge straight and the back edge in a large full curve backward, to accommodate the fullness of the buttocks, leaving the bottom edge of the strip wider than the top edge, as is the case with all the strips of the back; and the back curved edge of *b* I sew to the straight edge of *a*. Strip *c* is also cut with the front edge straight and the other edge curved, and the curved edge of strip *c* is sewed to the straight edge of strip *b*. Proceeding with the cutting I next cut strips *d*, *e*, and *f*, all with a straight front edge and a curved back edge, sewing as before the curved edge of each to the preceding straight edge. We have now completed the cutting and making up for one-half of what I term the "back" of the garment, although the pieces or strips *e*, *f*, come well round upon the side and front of the body, a comparatively perpendicular portion of the normal figure. The other half of the back of the garment is cut and sewed together in the same way, the curved edge of back strip *a*, as stated above, being sewed to the similar curved edge upon the similar back strip *a'*, and the two edges being united in a seam adapted to conform to the sacral curve of the figure.

The above described method of cutting a strip with the front edge straight and the back edge extended and joining a straight front edge to an extended back edge, in making the "back", instead of distributing the necessary fullness to both side edges, results not only, as stated above, in bringing the strain or tension of the garment around the back in a line parallel to the threads of the fabric so that there can be no stretching of the structure, and while also throwing an easy fullness of the supporter well back, thus providing room for the free play of the prominent buttock muscles, which act to maintain the upright position of the body and to overcome the tendency of the closely-fitting supporter to push up out of place in wearing. This results in the forward edges of the strips *f*, *f'*, being set on the side of the body at a slight overhanging incline toward the side edges of the front which are, as will be shown, at a somewhat lower level on the body than the side edges of the "back".

Passing now to the "front" of the supporter where the fullness to be provided for is upward from the pubic bones towards the waist instead of downwards from below the 5 waist over the buttocks, it will be seen that for the purpose of getting an accurate fit and maintaining the shape of the supporter, the same idea is observed in cutting out and sewing together the strips of fabric, a straight 10 edge being sewed to a curved edge. I cut the front in three pieces, the warp and weft of the fabric being observed in cutting straight lines. The two outside pieces h, h' , have both side edges straight. The middle 15 piece g , has both side edges curved so that a strip two inches wide at the pubic bones will be, say, three inches wide at the top line, or the middle strip may be considered as two pieces, with the two inner straight edges 20 sewed together and the outside edges curved. The bottom edges of the middle and outside strips conform, the former to the pubic bones and the latter to the junction of the thigh with the trunk. The longer straight edge of 25 an outside strip is sewed to the curved edge of the middle strip. The strips h, h' , are, of course, shorter than the middle strip g . And so, too, it should be stated the strips f, f' of 30 the back, which when the garment is completed are contiguous to the strips h, h' , and by a system of buckles and straps receive the whole strain of the front upon the back, are only of the same length as the strips h, h' .

In constructing a supporter for an enlarged 35 abdomen the front is preferably made as indicated in Figs. 6 and 7 wherein G is the middle strip hereinbefore described, g^a being the gore therein, H, H' the two side strips having both edges straight and J, J' the two 40 inserted strips having both edges on a curve.

The smoothness of the fit of the garment is preserved by vertical bones or steels t, t, t , etc., inserted in pockets along the upright 45 seams that have been described as made between the different strips of fabric, the said pockets being made from superfluous cloth at said seams, or formed of independent strips of fabric sewed upon the several seams. The front parts of the side strips or pieces 50 f, f' , have a number of these bones or steels, as shown, to provide supporting value to what would otherwise be a weak place under the straps and buckles, the method of attaching which will now be described. The said 55 straps (I find four on each side an average number) are secured at more or less intervals across the "front" by stitching. The lower strap A is secured at the lower front center line of the front, *i. e.* the center line of strip 60 g , and carried diagonally upward across the "front" (the necessary folds being made in the straps), following the general cut of the lower edge of the "front" across strips h, h' , and extending in free ends at an upward 65 angle from the outer side edges of the strips

h, h' , to meet two buckles K, K' , which are secured to the strips f, f' , as will be described. The next strap B is similarly secured across the "front" not quite parallel to strap A , being in a little nearer direct line across the 70 front, and has free ends to meet similar buckles L, L' , while succeeding straps C and D , and more if necessary, are likewise secured, but in still nearer transverse lines across the abdomen, and with their free ends 75 at a less angle, their number depending upon the prominence of the abdomen, and upon the necessary depth of the front required for a fit.

The buckles K, K', L, L' , etc., are secured 80 to one of the boned seams at the middle of said strips f, f' , by short straps similar to those attached to the front of the garment, but herein termed "attaching straps" to distinguish the two sets from one another, each 85 said attaching strap being sewed to its strip f or f' at a right angle to a seam or pocket for a boned upright t' , in said strip and then within the buckle (which is held at a downward angle to accurately meet the free end of its 90 respective strap from the "front") turned back upon itself and carried diagonally up and back to the seam or pocket, thus holding the buckle at a proper angle to meet the pull of the "front" straps and securing a wide, 95 evenly distributed pull around the strong well covered bony pelvis, the line of the pull being below the iliac crest at the sides and thus avoiding compression of the abdominal wall above said crest. By reason of the 100 slight set out of the pieces f, f' , and especially because of the angles at which the buckles are set to meet the free ends of the straps stitched across the front at a lower level and slanting upwards (but in a decreasing degree) 105 the horizontal line of tension around the pelvis at the back is deflected to a more or less upward and lifting pull upon the straps.

The bones t, t, t , inserted in the pockets of the "back" and the "front" besides preserving 110 the original shape of the supporter in wear, tend to distribute the strain of any one set of buckles and straps over the entire supporter.

Garter straps or hose supporters are used 115 with my improved abdominal supporter in many cases with advantage. They should be secured to the sides of the "back", preferably at e^2, e^2 , but may be secured to the front at g' or to both e^2, e^2 and g' ; for garters when 120 attached to the front exercise no depressing effect upon the contents of the abdomen such as results from attaching garters to a corset and throwing the strain upon the waist, and when attached to the "back" they assist in 125 holding the fullness of the lower edge of the back in place, as described, and in keeping the lower edge of the "front" taut. The garter straps to which garters (not shown) may be attached are marked R, R , etc. 130

Having thus described my invention, what I claim and desire to secure by Letters-Patent is:

1. An abdominal supporter having a back section and a front section with contiguous edges at the sides, the front section stiffened at intervals by vertical bones, a series of straps extending across the front section, secured to the bones thereof, and slanting upwards at each end of the front section at angles decreasing from bottom to top, and buckles carried by the back section and arranged at different angles from one another but each at right angles to the line of one of the straps.
2. An abdominal supporter consisting of a front and a back section the latter consisting of a series of pieces of fabric, the front edge of each piece being parallel to the line of threads

of the fabric while the opposite edge is curved 20 from the bottom towards the top thereby providing for the fit of the back, and the former consisting of three pieces of fabric both edges of the outside pieces being parallel to the line of the threads, while the inner 25 piece is curved on both edges from the top towards the bottom thereby providing for the fit of the front, bones at the meeting edges of the pieces of fabric in each section, and means for connecting the two sections at 30 their contiguous sides.

In testimony whereof I affix my signature in presence of two witnesses.

LYDIA ROSS.
